UNITED STATES PATENT OFFICE

109,006

DESIGN FOR A GARMENT BLOCKER

Winfield P. Brown and Jane W. Prest, St. Paul, Minn.

Application May 8, 1936, Serial No. 62,553

Term of patent 3½ years

To all whom it may concern:

Be it known that we, Winfield P. Brown and Jane W. Prest, citizens of the United States, residing at St. Paul, in the county of Ramsey and State of Minnesota, have invented a new, original, and ornamental Design for Garment Blockers, of which the following is a specification, reference being had to the accompanying drawing, forming a part thereof.

The characteristic features of our blocker consist in perforations and the arrangement thereof, and the specific arrangement of fabric bands in the relation and positions indicated on the garment blocker substantially of the configuration shown.

We claim:

The ornamental design for a garment blocker, as shown and described.
